(57) **CLAIM**

The ornamental design for a robot, as shown and described.

DESCRIPTION

FIG. 1 shows a front elevation view of a first embodiment of the robot of our new design, the first embodiment

showing a black display color around a peripheral portion of a lower portion of a display screen, wherein a graphical display in a central region of the lower portion of the display screen defined by a dash-dot-dash line is disclaimed;

FIG. 2 shows a top left-side front perspective view of the first embodiment of the robot of our new design, the first embodiment showing the black display color around the peripheral portion of the lower portion of the display screen, wherein a graphical display in a central region of the lower portion of the display screen defined by the dash-dot-dash line is disclaimed;

FIG. 3 shows a top right-side front perspective view of the first embodiment of the robot of our new design, the first embodiment showing the black display color around the peripheral portion of the lower portion of the display screen, wherein a graphical display in a central region of the lower portion of the display screen defined by the dash-dot-dash line is disclaimed;

FIG. 4 shows a bottom left-side front perspective view of the first embodiment of the robot of our new design, the first embodiment showing the black display color around the peripheral portion of the lower portion of the display screen, wherein a graphical display in a central region of the lower portion of the display screen defined by the dash-dot-dash line is disclaimed;

FIG. 5 shows a front elevation view of a second embodiment of the robot of our new design, the second embodiment showing a black surface color of a forward-facing portion of lower sides and a bottom portion of a display screen surround member, and a black display color around a peripheral portion of a lower portion of a display screen, wherein a graphical display in a central region of the lower portion of the display screen defined by a dash-dot-dash line is disclaimed;

FIG. 6 shows a right-side elevation view of the second embodiment of the robot of our new design, the second embodiment showing the black surface color of the forward-facing portion of lower sides and the bottom portion of the display screen surround member, and the black display color around the peripheral portion of the lower portion of the display screen, wherein a graphical display in a central region of the lower portion of the display screen defined by the dash-dot-dash line is disclaimed;

(Continued)

FIG. 7 shows a left-side elevation view of the second embodiment of the robot of our new design opposite that of FIG. 6, the second embodiment showing the black surface color of the forward-facing portion of lower sides and the bottom portion of the display screen surround member, and the black display color around the peripheral portion of the lower portion of the display screen, wherein a graphical display in a central region of the lower portion of the display screen defined by the dash-dot-dash line is disclaimed; FIG. 8 shows a top left-side front perspective view of the second embodiment of the robot of our new design, the second embodiment showing the black surface color of the forward-facing portion of lower sides and the bottom portion of the display screen surround member, and the black display color around the peripheral portion of the lower portion of the display screen, wherein a graphical display in a central region of the lower portion of the display screen defined by the dash-dot-dash line is disclaimed; FIG. 9 shows a top right-side front perspective view of the second embodiment of the robot of our new design, the second embodiment showing the black surface color of the forward-facing portion of lower sides and the bottom portion of the display screen surround member, and the black display color around the peripheral portion of the lower portion of the display screen, wherein a graphical display in a central region of the lower portion of the display screen defined by the dash-dot-dash line is disclaimed; and, FIG. 10 shows a bottom left-side front perspective view of the second embodiment of the robot of our new design, the second embodiment showing the black surface color of the forward-facing portion of lower sides and the bottom portion of the display screen surround member, and the black display color around the peripheral portion of the lower portion of the display screen, wherein a graphical display in a central region of the lower portion of the display screen defined by the dash-dot-dash line is disclaimed.

The broken or evenly-dashed lines are included to show structure of the robot that form no part of the claimed design.

1 Claim, 10 Drawing Sheets
